TYPEWRITER HEATER

Ralph Corvino, Charles W. Pedersen, and William R. Stone, New York, N. Y., assignors to Vari-Typer Corporation, a corporation of Delaware

Continuation of abandoned application Serial No. 296,516, June 30, 1952. This application December 27, 1954, Serial No. 477,956

The terminal portion of the term of the patent to be granted subsequent to December 28, 1970, has been disclaimed

3 Claims. (Cl. 197—6.5)

(Granted under Title 35, U. S. Code (1952), sec. 266)

The invention described herein may be manufactured and used by or for the Government of the United States of America for governmental purposes without the payment of any royalties thereon or therefor.

The present application is a continuation of application Serial No. 296,516, filed June 30, 1952, and now abandoned.

This invention concerns typewriters and in particular concerns typewriters in which the type face is heated for making the type impression. In the preferred embodiment of the invention the type is heated from the back thereof so that the printed impression can be made upon materials such as thermoplastic tubing without excessive heating of the tubing.

In forming printed impressions by typewriter upon thermoplastic tubing of the kind used as insulation upon electrical conductors, difficulty is encountered in making an impression that is permanent. Impressions made upon this kind of material have a tendency to smear and rub off. It has been proposed in the past to provide in connection with typewriters of this kind a heating element located adjacent the type face and the type ribbon and the material upon which the impression is to be made. This arrangement has proven unsatisfactory because of the fact that the high temperatures required in heating the type face result in softening of the thermoplastic material to the point where it is fatally damaged.

The present invention overcomes these difficulties by providing in connection with the kind of typewriter described a heating element that is disposed behind the type body on the opposite side of the body from the type face. The construction is such that the type body forms a shield between the heating element and the material upon which an impression is to be made at the type face. Heating of the type face is accomplished by conduction from the rear of the type body. The shielding afforded by the type body prevents overheating of the material upon which the impression is to be made.

An object of the invention is to provide a typewriter in which the type face is heated.

Another object is to provide a typewriter in which the type is heated by a heating element located behind the type body on the side opposite the type face.

Another object is to provide a typewriter in which the type is heated from behind the type body whereby the type body forms a shield between the heating element and the material upon which the printed impression is to be made.

Other objects and many of the attendant advantages of this invention will be readily appreciated as the same becomes better understood by reference to the following detailed description when considered in connection with the accompanying drawings wherein:

Fig. 1 is a top plan view of the rear portion of a typewriter.

Fig. 2 is a perspective view, with parts omitted and

2

broken away for clarity, as seen from above and to the lower left of Fig. 1.

Fig. 3 is a fragmentary front elevation, with parts omitted for clarity, as seen from the right of Fig. 1, and

Fig. 4 is a wiring diagram of the electrical circuit used in connection with the heating element.

In the drawings there is shown a typewriter having a carriage 11 mounted for movement from left to right and right to left as seen in Fig. 1. The carriage 11 is operatively associated with suitable conventional mechanism (not shown) for progressing it past the printing point 14 as the individual type selecting levers (not shown) are actuated to affect the typing operation. A support in the form of an anvil 15 fixed to the frame 16 of the typewriter has a shuttle 17, carrying embossed type, mounted thereon for movement about the periphery of the anvil 15 under control of type keys for presenting selective characters of type at the printing point 14. A hammer 19 is actuated by a conventional mechanism (not shown) to drive the flexible tube 20 against the selected type character to receive the type impressions. The hammer spring (not shown) is preferably slightly stronger than the standard spring normally used to supply the necessary force to collapse the tube 20 into a plane surface against the shuttle 17 while forming the printed impression. A ribbon 21 is interposed between the tube 20 and the type shuttle 17 in order to supply the necessary pigment for forming the type impression on the tube 20. A conventional ribbon shield 22 is interposed between the tube 20 and the ribbon 21. The shield 22 has an aperture at the printing point 14 to permit the tube 20 to contact the ribbon 21 at a point opposite the selected type on shuttle 17. The shield 22 serves to protect the tube 20 from marking by the ribbon 21 elsewhere than at the printing point 14. The ribbon shield 22 is conventionally mounted on arms 24 and 25 which are fixed in a frame 26 pivoted to the top plate 27 of the typewriter.

This general organization of hammer, type shuttle, ribbon and type shield is old in the art and is shown and described more completely in Patents 2,007,229 of July 9, 1935, issued to Frank H. Trego, and 1,936,594 of November 28, 1933, issued to Charles A. Fuchs, to which reference is made for a more complete disclosure.

The tube 20 is held in position on the carriage 11 by conventional clamps (not shown). This type of clamp is old in the art and is shown and described more completely in Patent 2,515,381 of July 18, 1950 issued to Henry Resch to which reference is made for a more complete disclosure.

According to the present invention, the anvil 15 is heated to an elevated temperature by a heating unit that includes among its elements a circular, metallic cap 28 mounted on top of the anvil and of the approximate diameter of the anvil and having a depending skirt in thermal contact with the top edge of the anvil throughout its circumference. The cap 28 is heated to elevated temperature by another element of the heating unit comprising an electrical resistance heating element 31 contained within the space defined by anvil 15 and cap 28, the heat of the cap being transmitted to the anvil and in turn to the shuttle 17.

Heating element 31 can be located anywhere within the space defined by anvil 15 and cap 28. For example, heating element 31 can be located inside of anvil 15 so that heating element 31 is disposed behind shuttle 17 and is on the opposite side of shuttle 17 from the type face. Thus shuttle 17 in effect forms a shield between heating element 31 and tube 20 upon which an impression is to be made by the type face of shuttle 17 at the printing point 14.

Heating element 31 is generally arcuate in shape. Heating element 31 comprises an arcuate tube 32 of suitably refractory material upon which is wound in the form of

a coil an electrical resistance wire 33 the ends 34 and 35 of which are connected in an electrical circuit as later described in connection with Fig. 4. Refractory tube 32 is mounted for support upon a core wire 36 the ends of which are bent downwardly at 37 with each lower extremity bent into a horizontal loop 38 that is fastened by means of a screw 39 to base 41 forming a part of the typewriter frame 16.

The ribbon 21 is a thermosensitive type ribbon that is capable of forming type impressions only when the type, the ribbon and the material to be typed on, or at least one of them, are at an elevated temperature so as to soften the ribbon pigment or the surface of the material, or both for the printing operation. A single use thermosensitive type ribbon known in the trade as branding tape, which is discarded after one passage past the printing point 14 has proved satisfactory for this purpose.

The ribbon feed mechanism for progressing the ribbon 21 past the printing point 14 may be of any suitable type. The one shown is similar to that in Patent 2,161,856 of June 13, 1939, issued to Ralph C. Coxhead, to which reference is made for a more complete disclosure. The ribbon 21 is supplied from a conventional spool and is passed through ribbon guide 47 and past the printing point 14 adjacent the ribbon shield 22 through a second ribbon guide 48 and between ribbon feed rolls 51 and 52.

The degree of heat required depends to some extent upon the size of the type characters being used and upon the particular composition of the material upon which the type impressions are to be formed. Variation in heating is provided for by a conventional rheostat 56 mounted at the rear of the typewriter and connected in electrical series with the resistance wire 33 of the heating element 31. The rheostat 56 is of the conventional variable resistance type, the amount of electrical current supplied to the heating unit 31 being regulated by setting the knob 57 in various positions.

To further control the supply of electrical energy to the heating unit 31, a conventional off and on electrical snap switch 61 is mounted on frame 16 and connected in series with the rheostat 56 and the heating unit 31. In addition, as a safety precaution a thermostat 62 is positioned adjacent printing point 14. The thermostat 62 may be of the enclosed conventional bimetallic element type containing a set of electrical contact points, the action of the thermostat being to open the electrical circuit passing through the heating unit 31 when the area adjacent heating point 14 attains an excessively high temperature. This thermostat is preferably set to open the circuit upon reaching a temperature of approximately 275° F. and is in the nature of a safety device only, not being operative unless the rheostat 56 is set so as to supply an excessive amount of electrical energy, all factors being considered, thus producing excessive heating of the shuttle 17 and the tube 20 to be typed.

The electrical connections may be made as shown in Fig. 4, the electrical system being connected to a suitable source of electrical power, customarily 110 volt alternating current. It will be apparent from a study of Fig. 4 that by maintaining the electrical switch 61 in an off-position, the heating unit 31 is not energized. By substituting a conventional ribbon for the branding tape previously described, it is possible to use the same machine for conventional typing on strands of material and the like which can be suitably engaged by the clamps.

In operation with the electrical system shown in Fig. 4 connected to a suitable source of power, rheostat 56 is set to supply the desired amount of electrical energy to heating element 31. Snap switch 61 is moved to the

on-position and heating element 31 is allowed to heat the shuttle 14 until the type face of shuttle 14 achieves the desired temperature. In the event that an excessive temperature at the type face of shuttle 14 is achieved, thermostat 62 is actuated to open the electrical circuit of Fig. 4 and thereby de-energize heating element 31.

Because heating element 31 is disposed behind type shuttle 17 and on the opposite side of type shuttle 17 from the type face, it is seen that heating of the type face is by conduction from the rear of the shuttle. Type shuttle 17 therefore forms a shield between heating element 31 and tube 20 upon which an impression is to be made at the type face. The shielding afforded by shuttle 17 prevents overheating of tube 20 and also heating of ribbon 21.

Obviously many modifications and variations of the present invention are possible in the light of the above teachings. It is therefore to be understood that within the scope of the appended claims the invention may be practiced otherwise than as specifically described.

We claim:

1. In a typewriter for printing with the aid of heat and having a thermosensitive type ribbon, an anvil having a cylindrical outer surface, an arcuate type shuttle having type characters embossed thereon and having an arcuate rear surface mounted for sliding movement along the outer surface of the anvil to index selected type at a printing point, and a cylindrical heat-control unit mounted above the anvil and comprising a cylindrical, metallic cap having a generally flat, circular portion and having a depending, cylindrical skirt in thermal contact with the anvil throughout its circumference, and an electrical resistance heating coil mounted within the space defined by the cap and anvil.

2. In a typewriter for printing with the aid of heat and having a thermosensitive type ribbon, an anvil having a cylindrical outer surface, an arcuate type shuttle having type characters embossed thereon and having an arcuate rear surface mounted for sliding movement along the outer surface of the anvil to index selected type at a printing point, and a cylindrical heat-control unit mounted above the anvil and comprising a cylindrical, metallic cap having a generally flat, circular portion and having a depending, cylindrical skirt in thermal contact with the anvil throughout its circumference, and an electrical heating means mounted within the space defined by the cap and anvil for heating the anvil and shuttle.

3. In a typewriter for printing with the aid of heat and having a thermosensitive type ribbon, an anvil having a cylindrical outer surface, an arcuate type shuttle having type characters embossed thereon and having an arcuate rear surface mounted for sliding movement along the outer surface of the anvil to index selected type at a printing point, and a heat-control unit mounted at the anvil and comprising a metallic cap covering the anvil and having a depending circular skirt in thermal contact with the anvil throughout its circumference, and an electrical resistance heating unit mounted in the space defined by the cap and anvil for heating the cap, anvil, and shuttle.
